UNITED STATES PATENT OFFICE.

JOHN GEORGE LEYNER, OF DENVER, COLORADO.

STRIKING-PIN FOR PISTON-HAMMER ROCK-DRILLING ENGINES.

No. 901,538.

Specification of Letters Patent.

Patented Oct. 20, 1908.

Application filed April 3, 1905. Serial No. 253,409.

To all whom it may concern:

Be it known that I, JOHN GEORGE LEYNER, a citizen of the United States of America, residing in the city and county of Denver and State of Colorado, have invented a new and useful Striking-Pin for Piston-Hammer Rock-Drilling Engines, of which the following is a specification.

My invention relates to a new invention which I term a hammer striking pin for fluid pressure, for rock drilling engines, and that is especially adapted for the piston hammer type of rock drilling engines, and that I especially use in connection with my drill bit rotating mechanism for rock drilling engines embodied in my Letters Patent No. 796,081, dated August 1, 1905.

The mechanism is illustrated in the accompanying drawings, in which,—

Figure 1 is a plan view of a rock drill embodying my invention. Fig. 2 is a central, vertical, longitudinal sectional view through the same. Fig. 3 is an elevation of the front end of the drilling engine. Fig. 4 is an elevation of the front end of the drilling engine, with the front cylinder head removed. Fig. 5 is a transverse, vertical, sectional view on the line 5—5 of Fig. 2. Fig. 6 is a plan view of the sleeve through which the feed screw passes, and which has an integral gear wheel at one end. Fig. 7 is a transverse, sectional view of the same, on the line 7—7 of Fig. 6. Fig. 8 is a sectional view in perspective, of the striking-pin-holding buffer sleeve. Fig. 9 is a side elevation of the drill-striking pin. Fig. 10 is a side elevation of the drill-holding gear chuck. Fig. 11 is a side elevation of the front cylinder head. Fig. 12 is a rear view thereof. And Fig. 13 is a perspective view of the drill-bit.

Similar letters of reference refer to similar parts throughout the several views.

Referring to the drawings: The numeral 1 designates the cylinder of my rock drilling engine. This cylinder is provided with an axial bore of two diameters, 2 and 3, the largest of which, 2, extends into it from its rear end, for about one-half of the length of the piston hammer's stroke, where it terminates in a square shoulder, 4, at the beginning of the smaller bore, 3, which continues from the shoulder to the end of the piston's portion of the cylinder. The entrance to the rear end of the cylinder bore is threaded, and receives a cylinder head, 5, which comprises a flange portion 6, with a projecting hexa-

gon nut 7, on its outside, and a hub portion on its inside. The hub portion is threaded to screw into the threaded bore of the cylinder until the flange bears tightly against the end of the cylinder.

At a short distance from the rear end of the cylinder I form on the cylinder a transverse cylindrical boss portion 8, in which is formed a circular air inlet aperture 9, the entrance of which is threaded to receive the threaded connecting end of the hose 10, which leads to a supply of compressed air. The air inlet aperture connects with a circumferential recess, 12, formed in the periphery of the bore of the cylinder, which forms the air inlet port of the cylinder.

Adjacent to the shoulder 4 and in the larger bore of the cylinder, a circumferential air inlet port, 13, is also formed, and the port 12 is connected to the port 13 by ports 14, that are drilled into the rear end of the shell of the cylinder in axial alignment with the axis of the cylinder, and in position to intersect the port 12 and to extend to and intersect the port 13, which is located in a circumferential rib 8^a, that surrounds the cylinder over the port 13.

The entrances to the port holes 14 are tightly plugged after they are drilled. At the front end portion of the smaller diameter of the piston's bore a circumferential exhaust port 16 is formed in the cylinder. This exhaust port is open to the atmosphere through an exhaust aperture 17, which extends through the bottom of the shell of the cylinder into it. In the bore of the cylinder I reciprocally mount a piston hammer 18, the peripheral surface of which is made in two diameters, 19 and 20, to fit the two diameters of the cylinder's bore.

The piston hammer is provided with an axial bore 21, which extends into it from its rear end to within a short distance from its front end. This piston is provided, adjacent to its rear end, with radial port holes 22, which extend from the exterior face of the piston hammer through its shell. These ports are preferably arranged so that a part of them will radiate at substantially a right angle to the axis of the hammer, and the remainder will stand at an obtuse forward angle from the interior base of the hammer, and they are also preferably arranged so that their entrances within the bore of the hammer are arranged in an alternating zigzag line, and their outer openings are in a straight

circumferential line. The forward end of the piston hammer at the inner end of its axial bore is provided with a radial row of port holes, 23, that extend from the interior bore 5 through the shell of the hammer. At the end of the cylinder's piston hammer bore, an axial bore 24 is formed, which is larger in diameter than the bore of the hammer, and at the end of the bore 24, a still larger bore 10 is formed in the cylinder that extends to its front or drill-bit holding end; substantially square shoulders 24^a and 25^a are formed between these three bores of the cylinder. The corners of the shoulder 25^a are, however, 15 preferably rounded. In the bore 24, I place a steel buffer sleeve, 26. This sleeve fits loosely but snugly, in the bore, and normally against the shoulder 24^a, formed between the piston hammer's bore and the bore 24, and 20 on the outer end of this sleeve an enlarged collar portion 27, is formed, which fits normally in the large end bore 25, against the shoulder 25^a formed between the bore 24 and the bore 25. Against the forward end of the 25 steel buffer sleeve, I place a rubber buffer ring 28, and against this rubber buffer ring I place a steel washer 29. This steel washer and the rubber buffer ring contain large axial apertures through which projects loosely one end 30 of a drill-bit holding chuck or sleeve, 30, which projects at one end into the end of the cylinder and through this steel washer and rubber buffer ring and also loosely into the sleeve 26, for a short distance of the sleeve's 35 length. The opposite end of the chuck projects forward beyond the end of the cylinder, and is inclosed by a hub, 30^a, formed on the front cylinder head 31. The opposite sides of the front end of the cylinder are provided 40 with lugs 32, to which one end of studs 33 are threaded.

The front cylinder head is provided with lug portions, 33^a, that are provided with holes that fit over the studs, and the nuts, 34, 45 are threaded to the free ends of the studs, which project through the holes in the cylinder head.

The drill-bit holding chuck is provided at about the central portion of its length with a 50 gear, 35, which is formed preferably by an enlarged integral portion, in the peripheral surface of which the teeth of the gear are formed. This gear portion of the chuck fits snugly but rotatably between the front cylinder head and the steel washer. This gear, 55 however, is not large enough in diameter to extend to the inner peripheral surface of the cylinder, and I fill up the space between the outside diameter of the gear and the inner 60 peripheral surface of the cylinder by a ring shaped hub portion, 31^a, that is formed integral with the front cylinder head and that projects from its inner side into the end of the cylinder between the gear and the inner 65 periphery of the cylinder. A portion of the

under side of this hub is cut away to allow the gear, 35, to mesh with a gear placed below it, as will be more fully explained hereinafter.

The steel buffer sleeve is provided at its 70 end facing the piston hammer with an axial aperture, 36, of smaller diameter than the aperture in its opposite end, into which the drill holding chuck extends, and in this aperture 36, I fit loosely the front end of a hardened steel pin, 37, the opposite end of which fits loosely into the adjacent end of the drill-bit holding chuck. Upon the body of this pin, I form a circumferential collar, 38, which fits loosely in the larger axial aperture 80 of the steel buffer sleeve, and normally rests against the shoulder formed between the larger aperture of this buffer sleeve and the smaller aperture 36. The drill-bit-holding-chuck does not extend into the larger aperture of the steel buffer sleeve to the collar formed on the steel pin, but stops at a short distance from it, and a compensating space is left within the steel buffer sleeve and between the end of the chuck and the collar of 90 the striking pin. This steel pin, 37, I term the striking pin, and the end of this striking pin that projects through the aperture 36, in the steel buffer sleeve, projects beyond the sleeve a short distance into the reciprocal path of 95 the piston hammer, and the compensating movement of this pin is to permit the striking pin to be driven forward when it is struck by the hammer within the drill-holding chuck.

The rock cutting drill-bit, 39, is preferably 100 formed of what is known as cruciform steel, and the shank of this drill-bit consists of a bar of any predetermined length of this character of merchantable steel, and the rock cutting lips are formed upon its outer end in 105 the usual manner. The chuck is provided with an axial aperture, 37^a, which is cruciform to correspond to the shape of the drill, and the shank end of the drill projects loosely 110 into the drill-holding chuck and this shank end is not manipulated in any way. It is free from shoulders or projections, and it consists simply of the natural end of this bar of steel projecting loosely into the drill-holding chuck and against the striking pin, and 115 into the short compensating or reciprocal movement of the striking pin. The drill-bit is held in operative relation to the rock in which it is drilling by properly feeding the cylinder forward in such a manner that the 120 shank end of the drill-bit is held against the end of the striking pin and the striking pin's collar is held against the shoulder formed between its smaller and larger apertures. Then when the piston hammer strikes the striking pin, the blow is imparted by the striking pin to the end of the drill-bit, and it is driven 125 into the rock and the compensating movement of the striking pin allows forward feeding movement of striking pin to compensate 130

for the blow of the piston driving the cutting points of the drill-bit into rock, and also for failure on the part of the operator to feed the cylinder to hold the drill-bit close up to or 5 with slight pressure against the rock.

A depending lug portion, 40, is formed on the cylinder, which contains an aperture, 41, through it, and a counter-bore, 42, is also formed in it concentric to the aperture 41. 10 In this counter-bore, I place a gear 43, the teeth of which mesh with the teeth of the drill holding chuck gear, 35. This gear 43 is provided with a hub portion 44, that fits rotatably in the aperture through the depending lug 40, and from this hub a long sleeve 45, extends forward under the cylinder to close to a nut 46, which is secured in a depending lug 48, formed on the rear end of the cylinder. This nut 46 is threaded and a 15 feed screw 47 is rotatably threaded to it, and this screw extends loosely through the gear 43, hub 44, and the sleeve 45, with the exception of its outer end, which is feathered to the feed screw in the following manner: The 20 feed screw 47 is provided with two key ways 48^a, which are cut through its threads on opposite sides of it, and the axial aperture in the outer end of the sleeve is reduced in diameter and the metal is swaged or drifted 25 away from the opposite side of the inner peripheral surface of the wall of this reduced axial aperture by drifts or swages, in such a manner as to leave two feather keys 49 depending from the inner periphery of the aperture. These feather keys are arranged and 30 adapted to fit slidably in the key ways in the opposite sides of the feed screw, so that when the feed screw is rotated the sleeve and gear will be rotated with it, and will also feed 35 along its length as the cylinder is moved, which movement of the cylinder is caused by the opposite or outer end of the feed screw being secured rotatably to the head portion, 49^a, of rearwardly extending arms 50, which 40 are secured at their inner end to a supporting shell 51. This supporting shell is provided with slide ways 52 on its opposite sides, and the cylinder is provided with guide ways 53, which are arranged and adapted to fit and 45 slide in the slide ways of the supporting shell. The bottom of the shell is provided with an inverted fan-tail or dove-tailed shaped circular hub, 52 which is adapted to be clamped by a stoping bar chuck in a well known 50 manner. The outer end of the feed screw is provided with a crank handle 54, which is secured to the feed screw in such a manner that the feed screw is rotatably journaled to the head portion 49^a of the arms 50 against 55 longitudinal movement. The front cylinder head depends down over the gear 43 and is provided with a hub portion through which the feed screw projects loosely.

The sleeve 45 is provided with axial apertures, 45^a, which are placed through its shell

opposite the exhaust port 17, which permit the exhaust air to enter the sleeve and keep the screw free from dust and lubricate it.

On the rear end of the cylinder I form or secure by any suitable means an arm 55, 70 which is positioned to stand over the slide ways of the shell, and on the opposite end of the shell in the path of this arm I form or secure a projecting abutment stop 56, against which the arm strikes when the cylinder is 75 fed forward in the shell as far as it should be in the shell, and which limits the operative feeding stroke of the cylinder, and prevents the cylinder being fed too far forward in the shell. 80

The operation is as follows: When the screw is rotated by the crank, the cylinder is fed to and fro in its supporting shell, as the nut 46, which is attached to the cylinder, feeds to and fro depending on which way the feed screw is turned, and the sleeve 45 and its gear 43 turn with the feed screw, being held by its feather keys, and they also slide along the feed screw with the cylinder. As the gear 43 is rotated by the feed screw, it rotates 90 the drill holding chuck gear, and the drill holding chuck rotates the rock cutting drill-bit. The piston hammer and ports operate in the following manner: Assuming the piston to be at the end of its forward stroke in 95 the cylinder as shown in Fig. 2, the compressed air flows from its source of supply through the hose 10 into the inlet port 12 and through the longitudinal port 14 to the port 13, and entering the cylinder between the 100 shoulder 4 of the cylinder and the shoulder 20^a of the piston hammer, moves the piston backward to the rear end of its stroke in the cylinder, and when the ports of the piston 105 hammer pass the inlet port 12 the air rushes from the inlet port into and through the plurality of radial ports 22 into the interior of the piston hammer and to the rear end, cushioning it just before it strikes the cylinder head and starting it back and throwing it forward and impinges it with great velocity 110 against the end of the striking pin as the air flows into the interior of the piston hammer in much greater volume than against its shoulder through the port holes 22, when it reaches 115 the forward end of its stroke, its exhaust ports register with the exhaust port 16 and the air in the interior of the piston hammer flows out to the atmosphere through the exhaust ports 23. The air then again enters 120 the inlet port 9, and the reciprocal stroke is repeated. The piston hammer strikes the striking pin with great rapidity, causing it to strike the end of the rock cutting drill bit each time it is struck by the piston hammer, and the operation rotates the crank handle 125 and the feed screw and feeds the cylinder forward in its supporting shell just fast enough to keep the drill-bit in operative relation to rock. In case, however, the drill-bit is so 130

loosely held in the drill chuck that the striking pin does not strike it or is not in the drill chuck, the striking pin is then driven against the adjacent end of the drill chuck, and the 5 piston hammer strikes against the end of the steel buffer sleeve, which cushions against the rubber buffer and the steel washer and the gear and cylinder head. The rubber buffer cushions the blows, however.

10. It will be seen by the above that by the use of the striking pin I am enabled to use rock cutting drill bits having straight natural bar shanks of any kind or character of cross section, without doing any work on them or providing them with collars or shoulders or lugs or other members that are intended to bear against the end of the cylinder and define the distance the striking end of the shank shall extend into the cylinder; thus enabling me 15 to do away or dispense with all that character of work and greatly cheapen the cost of the rock cutting drill-bits. The drill bits are thrown around the floor of shafts, stopes, and tunnels, and get covered with grit, sand, 20 and mud, and this striking pin, taken in connection with the steel sleeve, also prevents 25 this sand, mud, and grit from working into the cylinder of the piston hammer.

Although I preferably use cruciform steel, 30 still my invention contemplates the use of any form of cross-section of any merchantable tool steel, used for cutting rock, as round, square, hexagon, triangular, ribbed, or cross-ribbed, or of any polygonal form.

35. Having described my invention, what I claim as new and desire to secure by Letters Patent, is:—

1. In a rock drill, a drill-bit, a hammer piston, a striking pin inserted therebetween 40 and adapted to receive and impart blows of said hammer piston to said drill-bit, and a buffer device arranged to receive direct blows from said hammer piston when the striking pin is in its lowermost position.

45. 2. In a rock drill, a drill-bit, a hammer piston, a striking pin inserted therebetween and adapted to receive and impart blows of said hammer piston to said drill-bit, and an elastic buffer device arranged to receive direct 50 blows from said hammer piston when the striking pin is in its lowermost position.

3. In a rock drill, a drill-bit, a hammer piston, a striking pin inserted therebetween and adapted to receive and impart blows of 55 said hammer piston to said drill-bit, and an independently-mounted buffer device arranged to receive direct blows from said hammer piston when the striking pin is in its lowermost position.

60. 4. In a rock drill, a drill bit, a striking-pin, a hammer-piston for striking the striking-pin, and an elastically mounted buffer device arranged to receive the inoperative blows of said hammer-piston.

5. In a motive fluid hammer-piston rock 65 drilling engine, the combination with the cylinder and the hammer-piston, of a drill-bit holding chuck mounted in said cylinder, provided with an enlarged portion, a steel buffer sleeve mounted in said cylinder in the reciprocal path of said hammer-piston, and arranged to fit over the end of said chuck, a resilient buffer ring and a steel washer mounted on said chuck between said steel buffer sleeve and said enlarged portion of said chuck, 75 said buffer sleeve having an axial aperture of two diameters, arranged to form a shoulder in the front end of said sleeve, a pin reciprocally mounted in said sleeve, and arranged to project normally beyond the said 80 sleeve into the reciprocal path of said hammer-piston, a collar on said pin arranged to have a sliding movement between the shoulder in said steel buffer sleeve, and the adjacent end of said chuck, and adapted to define the reciprocal compensating movement of said pin, relative to the reciprocal strokes of said hammer-piston, and a drill-bit adapted to be supported by said chuck against said pin, substantially as described. 90

6. In a rock drill, the combination of a cylinder and a hammer-piston of a drill chuck, a drill-bit, and a buffer device between the drill chuck and said hammer-piston, and a striking-pin, reciprocally mounted between 95 said hammer-piston, and said drill-bit, and adapted to receive and impart the blows of said hammer-piston to the drill-bit, substantially as described.

7. In a rock drill, the combination of a cylinder, a hammer-piston, a drill chuck, and a drill-bit, with a drill-bit striking-pin interposed between said hammer-piston and said drill-bit, and adapted to receive the blows of said hammer-piston, and impart them to said 105 drill-bit, and a steel sleeve, and a resilient buffer device adapted to cushion the inoperative blows of said hammer-piston. 100

8. In a fluid-pressure rock drill, a cylinder, a non-revolvle hammer piston, a drill-bit, a 110 separate striking pin, and a revoluble drill-chuck.

9. In a rock drill, a cylinder, a non-revolvle hammer piston, a striking pin, a revoluble drill-chuck, and a drill-bit reciprocable in 115 but rotatable with said chuck.

10. In a rock drill, a cylinder, a non-revolvle hammer piston, a drill-bit, a separate striking pin, and a revoluble drill-chuck receiving said drill-bit and striking pin. 120

11. In a rock drill, a cylinder, a hammer piston, a striking pin having a circular end, a drill-bit having an angular shank, and a revoluble drill-chuck having a circular opening receiving said striking pin and an angular opening receiving said drill-bit. 125

12. In a rock drill, a cylinder, a non-revolvle hammer piston, a striking pin, a revol-

luble drill-chuck, and a buffer arranged to receive the inoperative blows of said hammer piston.

13. In a rock drill, a cylinder, a non-revoluble hammer piston, a striking pin, a revoluble drill-chuck, and an annular buffer surrounding said striking-pin and arranged to receive the inoperative blows of said hammer piston.

10 14. In a rock-drilling engine, a revoluble,

non-reciprocable chuck, a drill-bit mounted to rotate with and reciprocate in said chuck, a reciprocable striking-pin, and means for imparting a blow to said striking-pin.

In testimony whereof I affix my signature 15
in presence of two witnesses.

JOHN GEORGE LEYNER.
